UNITED STATES PATENT OFFICE.

DAVID F. TABER, OF NEW YORK, N. Y.

STEAM-BOILER-TUBE CLEANER.

No. 839,524.

Specification of Letters Patent.

Patented Dec. 25, 1906.

Application filed June 23, 1906. Serial No. 323,171.

To all whom it may concern:

Be it known that I, DAVID F. TABER, a citizen of the United States, residing in the city of New York, borough of Brooklyn, county of Kings, and State of New York, have invented certain new and useful Improvements in Steam-Boiler-Tube Cleaners, of which the following is a specification.

My improvements relate to the class of devices known as "blowers" for injecting steam into and through boiler-tubes for the purpose of dislodging and removing soot and other solid products of combustion therefrom, and more especially to tube-cleaning blowers to be installed in the rear walls of return tubular-boiler furnaces, substantially as set forth in my concurrent application, Serial No. 319,050, filed May 28, 1906, in which the distinguishing feature is the use of an automatically rotatable and retractable steam-nozzle. As set forth in said concurrent application, prior thereto steam-boiler-tube cleaners were only applicable to return-tube-boiler furnaces the back walls of which were accessible from the rear. In other words, there had to be sufficient space behind the furnace in which to situate and actuate the means, as a crank, by which the steam-nozzle was rotated. This difficulty I obviate in said prior application by rendering the nozzle automatically rotatable and feeding steam thereto from the side of the boiler-furnaces, so that the blower can be applied to the rear wall of a furnace even though the back thereof abuts against a partition, wall, or other obstruction.

The object of my present invention is in a similar manner to afford a comparatively simple inexpensive steam-blower which may in like manner be embedded in the rear wall of a return-tube-boiler furnace so situated as to be inaccessible from the rear, which blower may be positively operated manually from the side of the furnace in such manner that the position or speed of rotation of the steam-injecting nozzle may be effectually regulated and controlled or varied to suit requirements of use. Thus the injected steam may be directed temporarily against a certain section or into certain tubes of the boiler or the speed of rotation regulated to effect the desired result without wasteful diffusion of steam, &c.

To this end my present invention consists, primarily, in rotating and controlling an automatically-retractible steam-injector nozzle by means of a bevel-gear feathered to a rear

axial extension or spindle on the nozzle in such manner as to be rotatable therewith while admitting of the longitudinal movement of the said spindle and steam-nozzle within its casing, said feathered gear being in turn actuated by a bevel-gear on the inner end of a shaft extending through the steam-supply pipe, substantially as hereinafter set forth, and, secondarily, in certain other features in the construction and arrangement of parts hereinafter described and claimed specifically.

In the accompanying drawings, Figure 1 is a sectional elevation of a portion of the rear of a return-tube boiler and furnace to which my tube-cleaning blower is applied. Fig. 2 is a horizontal section taken upon plane of line 2 2, Fig. 1. Fig. 3 is a sectional elevation of my improved blower, taken upon plane of line 3 3, Fig. 1, partly broken away and upon a larger scale, the nozzle being shown in its retracted position. Fig. 4 is a like view, the nozzle being shown as advanced under steam-pressure. Fig. 5 is a side elevation of the nozzle; Fig. 6, a central longitudinal section through the casing; Fig. 7, a transverse section taken upon plane of line 7 7, Fig. 6, and upon a still larger scale. Figs. 8 and 9 are respectively rear and front elevations of the nozzle upon the same scale as Fig. 7. Figs. 10 and 11 are respectively front and rear elevations, upon the same scale, of the nozzle-gear.

A represents the rear end of a return-flue boiler of any desired type or construction, and B the rear wall of the furnace inclosing the end of the boiler and the rear extension of the combustion-chamber C.

Embedded in the rear wall B, with its longitudinal axis by preference practically or substantially coincident with the center of the area occupied by the boiler-tubes to be cleaned, is the casing D, consisting of a cylindrical front portion d and a convergent or tapering rear portion d', into which latter opens a lateral port d², said port communicating through a pipe or conduit E with a steam-supply pipe F through the medium of the head or elbow f and coupling f', the steam-supply pipe F being provided with a valve f². The pipe E, supplying steam through the port d² to the shell or casing D, is preferably inclined downward from said shell D, as indicated in Fig. 1, and the side walls of the rear portion d' of the casing D are tapered or inclined to facilitate the drawing off of water

of condensation into and through the conduit E and to the head or elbow f, from which it may be drawn off through a pet-cock f'.

5 The recess b in the rear wall B, in which the shell D is embedded, is preferably longer than said shell by approximately the extent of protrusion of the nozzle N beyond the shell D when the nozzle is advanced under 10 the pressure of the steam, so that the head or face n of the nozzle N will be nearly, but not quite, flush with the inner surface of the wall B when the nozzle is in use, the object being to advance the nozzle N sufficiently to give 15 free and independent clearance to the jets of steam issuing from the nozzle without exposing the latter to direct contact with the incandescent gases within the combustion-chamber C.

20 At the inner end of the casing D is an annular shoulder d³, consisting of a ring screwed or otherwise rigidly attached to said casing after the nozzle N has been placed within the 25 said casing. The external diameter of the main or cylindrical portion n' of the nozzle N is of a diameter but slightly less than the inner diameter of the ring or annular shoulder d³ in the casing D, so as to fit snugly therein, and the rear portion of the nozzle N is formed 30 with a corresponding annular shoulder n², fitting snugly within the cylindrical portion of the casing D. Between these two shoulders d³ and n² (or their equivalent, for it is obvious that the shoulders need not necessarily 35 extend continuously in a complete circle, but may each be subdivided into a series of bearings with like result) is interposed a coiled and compressed spring S, which tends constantly to hold the inner end of the nozzle 40 against the annular shoulder or seat d⁴ in the casing D, which is the normal position of the nozzle when not in actual use. It will be seen that in this normal position the nozzle N is entirely within the casing D.

45 Made integral with the nozzle N is an axial spindle or stem n³, connected with its inner end by radial arms n⁴, sufficient in number to support the spindle n³ rigidly without materially obstructing the admission of steam to 50 the chamber n⁵ within the nozzle N, the outer or front end of which chamber n⁵ is closed by the relatively thick head n⁶. Through this head n⁶ extend a series of steam-passages n⁷, all but the central one of which converge inwardly toward the longitudinal axis of the nozzle, so as to deflect the steam escaping from the nozzle N over a relatively wide area 55 and inject the steam into the various tubes a of the boiler A, the said passages n⁷ in the nozzle-head n⁶ being sufficient in number and so arranged as to meet the requirements of the class and size of boiler to which the blower is to be applied.

The spindle n³ passes through a centralizing and supporting bearing d⁵, connected

with the casing D by radial arms d⁶, said arms and bearings being made rigid and integral with said casing. Said spindle n³ is formed with a longitudinal groove n⁸ for the reception of and engagement with a tongue 70 q on the rotatable gear G, so that the spindle and nozzle will rotate with said gear while free to move longitudinally with relation to the casing. This spindle-gear G is held thereon and against the bearing d⁵ by reason 75 of its engagement with a driving-gear h upon the inner end of the driving-shaft H, which extends through the conduit E and is supported at the inner end thereof by a bearing e, which is centralized and supported by 80 the arms e', said arms and bearing being integral with the conduit E. The outer end of the driving-shaft H passes through a stuffing-box f' on the head or elbow f and has attached to it a wheel-crank h' or other mechanical expedient by which the shaft may 85 be rotated.

In use steam being admitted through the valve f² passes through the coupling-pipe f', elbow f, conduit E, and into the casing D, where it forces the nozzle to protrude, as illustrated in Fig. 4, the steam being finally ejected through the passages n⁷ across the combustion-chamber C into and through the boiler-tubes a, all of which are reached and 95 blown in this manner by reason of the rotation of the nozzle, which is effected by hand through the medium of meshing gears G h, shaft H, and crank h'.

It is to be understood that any well-known 100 or desired mechanical expedient may be resorted to for the purpose of moving the spindle-gear thereon in such manner that the spindle while rotating with said gearing shall be free to move longitudinally through the 105 same with like result, and I do not, therefore, confine-myself in this respect to the particular tongue-and-groove arrangement herein shown.

What I claim as my invention, and desire 110 to secure by Letters Patent, is—

1. In a device of the character designated, the combination with the inclosing shell and means for supplying steam under pressure thereto, of a longitudinally-movable nozzle, 115 a spiral spring surrounding said nozzle and interposed between it and the inclosing shell, one end of said spring resting against a shoulder on the shell and the other against a shoulder on the nozzle, and means for positively 120 rotating the nozzle on its longitudinal axis, for the purpose described.

2. In a device of the character designated, the combination with the inclosing shell and means for supplying steam thereto, of a nozzle having an axial spindle, a gear mounted thereon by means which admit of the longitudinal movement of the spindle while insuring its rotation with the gear, a driving-gear meshing with said spindle-gear, means 130

for rotating said driving-gear, and a spring surrounding said nozzle and interposed between it and the inclosing shell, one end of said spring resting against a shoulder on the shell and the other against a shoulder on the nozzle, for the purpose described.

3. In a device of the character designated, the combination of an inclosing shell, means for supplying steam under pressure thereto, a nozzle having a spindle formed with a longitudinal groove, a gear on said spindle formed with a tongue fitting said longitudinal groove, a driving-gear meshing with said gear on the nozzle-spindle, means for rotating said driving-gear, and a spring interposed between said shell and said nozzle, for the purpose described.

4. The combination with the inclosing shell and means for supplying steam under pressure thereto, of a nozzle having an axial spindle, a gear mounted thereon by means which admit of the longitudinal movement of the spindle while insuring its rotation with the gear, a driving-gear meshing with said spindle-gear, means for rotating said driving-gear, and a spring interposed between said shell and said nozzle, for the purpose described.

5. The combination with a return-tube boiler and furnace of a nozzle-inclosing shell embodied in the rear wall of the boiler-furnace in a recess opening into the combustion-chamber, means for supplying steam under pressure to said inclosing shell, a lon-

gitudinally-movable nozzle in said shell, a spring interposed between said nozzle and said shell, an axial spindle on said nozzle, a gear on said spindle mounted thereon so as to rotate therewith while admitting of the longitudinal movement of the nozzle and spindle, a driving-gear meshing with said spindle-gear, and means for rotating said driving-gear, for the purpose described.

6. The combination with a return-tube boiler and furnace, of a nozzle-inclosing shell embedded in the rear wall of the boiler-furnace in a recess opening into the combustion-chamber, a conduit communicating with said shell and extending therefrom through the rear wall of the furnace to the side thereof, means for supplying steam under pressure to said conduit, a longitudinally-movable nozzle in said shell, a spring interposed between said nozzle and said shell, an axial spindle on said nozzle, a gear on said spindle mounted thereon so as to rotate therewith while admitting of the longitudinal movement of the nozzle and spindle, a driving-gear meshing with said spindle-gear and mounted upon a shaft extending through said steam-conduit in the rear wall of the furnace, said shaft, and external means for rotating said shaft manually, for the purpose described.
